United States Patent Office.

CHARLES E. BANCROFT, OF MONTPELIER, VERMONT.

Letters Patent No. 96,867, dated November 16, 1869.

IMPROVEMENT IN SEAMING-MACHINE.

The Schedule referred to in these Letters Patent and making part of the same.

To all whom it may concern:

Be it known that I, CHARLES E. BANCROFT, of Montpelier, in the county of Washington, and State of Vermont, have invented a new and valuable Improvement in Seaming-Machines; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of a central vertical section of my invention, taken longitudinally.

Figure 2 is a top view of the same.

Figure 3 is a front view of the same.

My invention relates to double-seaming machines for tin-work, and consists, mainly, in the construction and novel arrangement of devices, whereby the required pressure on the work, between the forming-disks, is accomplished automatically.

The letter A, of the drawings, designates the bed-piece of my machine, having the flanches *a a* on each side, upon the lower edges of which it rests.

The longitudinal slot *z* is formed in the central portion of the bed-piece.

B designates a metal frame or support, whose foot-plate *b* is secured to the bed-piece by screws.

The upright *b'* and strengthening-rib *y* support the ledge *v*, turned upward at the ends to form bearings for the shaft *e* of the vertical forming-disk C.

These bearings are rendered firm by the brace *t*.

D represents a metal frame or support, whose foot-plate, *d*, slides between the flanches *a a* on the upper surface of the bed-piece A, being secured firmly to the same, when in proper position, by the bolt and nut *s*, operating through the slot *z*.

The upper part of the support D is turned forward, to form the upper bearing, *l*, of the vertical shaft *e*, whose lower end revolves in a cup or bearing formed in the head of the elevating-screw P.

Above the upper bearing-plate *l*, the vertical shaft *e* forms an elbow, and again turns upward, its upper end constituting the pintle, about which the horizontal forming-disk E revolves.

The horizontal disk E can be removed, and one of different size employed in its place, when it is so desired.

A guard or stop, *h*, is fastened to the vertical shaft *e*, below the plate *l*, to prevent the horizontal disk E from swinging beyond a certain point.

This is accomplished by the striking of the projecting arm or stop *h* against the edge of the support D.

Under the ledge *v*, near its forward end, is pivoted the horizontal clamp-wheel F, forming a counter-support to the outer portion of the vertical disk C, when in operation, and preventing any springing or friction of the same.

In the head of the elevating-screw P are the holes *n n*, for the reception of the end of a small lever, whereby it is turned.

K designates the hand-crank, by means of which the machine is operated.

The horizontal disk E is adjusted, vertically, by turning the elevating-screw P, and, horizontally, by sliding the frame D, the bolts having been previously loosened.

The work having been entered, in position, between the disks, the hand-crank K is turned in the direction indicated by the arrow, when the horizontal disk E is immediately drawn against the vertical disk C, and the work of seaming or bending the metal plate between them easily and readily performed.

When it is desired to remove the work from between the forming-disks, a reverse movement of the crank K will throw the horizontal disk off, or cause it to turn away, on its eccentric shaft *e*, loosening the pressure on the work at once.

The centre of the bearing of the vertical shaft *e*, in the plate *l*, is usually taken to the left of the perpendicular, erected on the central point of the lower bearing in the head of the screw P. Thus, a slant is obtained in the vertical shaft *e*, which is advantageous in tightening on the work, and in loosening it from between the horizontal shoulder of the disk C and the horizontal surface of the disk E.

The machine will work excellently well, however, with a perpendicular shaft.

Sometimes, instead of the single eccentric vertical shaft *e*, I employ two shafts, one, upon the top of which the horizontal disk revolves, having its bearings in arms extending out from the other, which has its bearings in the plate *l* and elevating-screw P.

What I claim as my invention, and desire to secure by Letters Patent, is—

1. The upright shaft *e*, arranged with a cam or bend in its upper part, and supporting the horizontal disk of a double-seaming machine, as described.

2. In combination with the horizontal disk of a double-seaming machine, the automatic cam-shaft *e*, having elevating-screw P and stop *h*, as shown and described.

3. The double-seaming machine herein described, having the slotted base A, standards B D, vertical disk C, clamp-wheel F, horizontal disk E, made removable, and upright cam-shaft *e*, stepped in the head of the elevating-screw P, and having the stop *h*, all constructed and arranged to operate as specified.

In testimony that I claim the above, I have hereunto subscribed my name, in the presence of two witnesses.

CHARLES E. BANCROFT.
